CLAIM

The ornamental design for a constant velocity joint, as shown and described.

DESCRIPTION

FIG. 1 is a front, left, top perspective view looking rearward of a constant velocity joint according to one embodiment of the present invention;

FIG. 2 is a right, rear, top perspective view looking forward thereof;

FIG. 3 is a left side elevational view thereof, the right side elevational, top plan view and bottom plan view being identical;

FIG. 4 is a front elevational end view thereof;

FIG. 5 is a rear elevational end view thereof; and,

FIG. 6 is a perspective view of a portion thereof shown installed in a vehicle.

The broken lines showing of a vehicle in FIG. 6 illustrates environment which forms not part of the claimed design.
